UNITED STATES PATENT OFFICE.

JOHN WALTER LEONARD AND HARRY EDGAR BROWN, OF WASHINGTON, PENNSYLVANIA.

ATTACHMENT FOR OIL-WELL APPARATUS.

1,031,562.

Specification of Letters Patent.

Patented July 2, 1912.

Application filed October 26, 1909, Serial No. 524,687. Renewed March 21, 1912. Serial No. 885,371.

To all whom it may concern:

Be it known that we, JOHN W. LEONARD and HARRY E. BROWN, citizens of the United States, and residents of Washington, in the county of Washington and State of Pennsylvania, have invented a new and Improved Attachment for Oil-Well Apparatus, of which the following is a full, clear, and exact description.

10 Our invention relates to clutches to be applied to machinery adapted to be driven by internal combustion engines, and has for its object to provide an apparatus which may be quickly adjusted to the shaft of a 15 steam engine, the cylinder of which has been replaced by one of the internal combustion type, with the bearing of the extended shaft on which the clutch is mounted, held in rigid relationship to the cylinder of the engine on a pivoted support to prevent fracture of the shaft by the working of the engine on its bed, relatively to the said bearing. The clutch has outer disks secured to the shaft, between which 20 are disposed two pulleys which are separated by a third disk secured to a sleeve mounted on the shaft, there being also a second disk secured to the sleeve. One of the outer disks has ears and there are also 25 ears on the said second disk secured to the sleeve, which project through the said outer disk, dogs being pivoted to the ears; the dogs pivoted to the ears on the outer disks 30 engaging studs on the said second disk and the dogs pivoted to the ears on the said second disk engaging the studs on the outer disk to clamp either of the pulleys as desired, means being provided for operating the dogs. A grooved pulley is secured to 35 the band wheel, a belt being connected with the band wheel and a rope being connected with the grooved pulley, the belt being also disposed around a pulley of the clutch and the rope being crossed and disposed around 40 the band wheel, a belt being connected with the band wheel and a rope being connected with the grooved pulley, the belt being also disposed around a pulley of the clutch and the rope being crossed and disposed around 45 a grooved pulley of the clutch.

In this specification we will describe the preferred form of our invention, but it will be understood that we do not limit ourselves thereto, as we consider ourselves to be entitled to all forms and embodiments of the invention which may be held to fall within the scope of the appended claims.

Reference is to be had to the accompanying drawings forming a part of this specification, in which similar characters of ref-

erence indicate corresponding parts in all the figures, in which—

Figure 1 is an elevation showing our invention as applied to oil well machinery; Fig. 2 is an enlarged plan view showing the extension shaft and the clutch as applied to the engine; Fig. 3 is an enlarged sectional view showing the clutch; Fig. 4 is an enlarged sectional view on the line 4—4 of Fig. 2; Fig. 5 is an enlarged sectional view on the line 5—5 of Fig. 2; Fig. 6 is an elevation of the pivoted support for the outer bearing for the extension shaft; Fig. 7 is an elevation of the pulley which is bolted to the band wheel; and Fig. 8 is a sectional view on the line 8—8 of Fig. 7.

By referring to the drawings, it will be seen that the oil well apparatus 10 is of the usual type and it is driven by a cable 11, which is disposed on a pulley 12, journaled in the oil well apparatus, the cable 11 also being disposed on a pulley on a band wheel 13, and a belt 14 disposed on a pulley on the band wheel 13 and also disposed on a pulley 15 of the clutch, connects the engine with the band wheel, so that when the engine is in operation it will transmit power to the band wheel and the band wheel will transmit power to the oil well apparatus 10, by means of the cable 11 and the pulley 12.

In the oil well fields at the present time steam engines are used, and the belt 14 is disposed on a pulley secured to the shaft 16 of the engine, but it will be understood that this is impossible when an internal combustion engine is used, because of the difficulty in reversing the engine.

Our invention has in view the application of a cylinder of an internal combustion engine to be secured to the old engine bed, from which a steam cylinder has been removed, and the application of the improvements which will hereafter be described in full, which will permit the band wheel 13 to be reversed while the engine is continuing in operation, with the shaft 16, which is the old steam engine shaft, rotating in the same direction. This we do by providing a second pulley 17 which is connected by a crossed cable 18 with a pulley on the band wheel 13. The pulley 17 is greater in diameter than the pulley 15, and inasmuch as the cable 18 is disposed on a smaller pulley on the band wheel than that on which the belt 14 is disposed, it will be seen that

when the pulley 17 is connected with the engine, the oil well apparatus will be driven more rapidly, the pulley 17 and the cable 18 being used to lower devices into the oil well, while the pulley 15 with its belt 14 is used to lift tools and material from the well.

Keyed on the shaft 16 is a sleeve 19, the sleeve 19 having a disk 20 disposed in close proximity to the inner bearing, while to the outer end of the sleeve is secured an extension shaft 21, which at its outer end is journaled in a bearing 22, which is mounted on a support 23, which is pivoted to a bed 24. The support 23 is divided into two sections, the lower one 25 having a bolt 26 secured thereto, the bolt 26 being disposed in a slot 27 in the upper member. This construction is provided to permit the adjustment of the height of the bearing 22. A tie rod 28 is bolted to a flange 29 secured to the bearing, the other end of the tie rod being secured to an engine cylinder 30. An extension rod 31 is secured to the engine frame 32 and to the tie rod 28, to keep the tie rod extended at the point where it is secured to the bearing. These features are provided to prevent any breakage of the shaft by any abnormal vibrations of the engine relatively to the shaft, the tie rod making certain that at all times the shaft will be disposed in proper relationship to the engine cylinder, its piston and connecting rod. On the extension shaft 21, close to the sleeve 19, is disposed a second sleeve 33, there being disks 34 and 35, one integral with and the other attached to said sleeve. There is also a disk 36 which is secured to the extension shaft 21. On the sleeve 19, between the disks 20 and 34, is disposed the pulley 15, the sides of the disks 20 and 34 converging toward their peripheries and the sides of the pulley 15 converging toward the shaft, so that the disks 20 and 34 will fit the sides of the pulley snugly. The pulley 17 is mounted on the sleeve 33, and against one of its sides a side of the disk 34 is disposed, the pulley 17 fitting the side of the disk 34, so that by frictional contact it may rotate therewith. On the outer side of the pulley 17, there is an annular groove 37 in which is disposed a flange 38, which is secured to the disk 36. In oppositely disposed openings 39 in the disk 36, are disposed ears 40, to which are pivoted dogs 41, the dogs having heads 42 which are adapted to engage studs 43 secured to the flanges 38. To oppositely disposed ears 44 on the disk 36 are pivoted dogs 45, the dogs 45 having heads 46 which are adapted to engage studs 47 which are secured to the disk 35 and which project through openings 48 in the disk 35. On the extension shaft 21 is disposed a collar 49, the collar 49 having an annular groove 50 in an extension 51. The collar 49 is provided to engage an arm 52 of the dog

41 and an arm 53 of the dog 45, the arm 53 being disposed at one side of the collar and the arm 52 being disposed at the other side. In the groove 50 is disposed a boss 54, mounted on an arm 55, the arm 55 being pivoted to a lever 56 which is secured to a cap 57, disposed on the journal 22. There is a spiral groove 58 in the bearing 22 and in this groove 58 is disposed a boss 59, which is secured to the cap 57, so that when the lever 56 is operated, the cap 57 will be forced either inwardly or outwardly, thereby by means of the arm 55, with its boss 54, to operate the collar 49, by means of its groove 50 in its extension 51, by which means the dogs 41 and 45 are operated.

Figs. 7 and 8 of the drawings show a pulley 60 which is adapted to be bolted against the usual pulleys found on a band wheel 13, which is being used to transmit power from a steam engine to oil well apparatus, the crossed cable 18 being disposed on this particular pulley 60.

In using our invention, the engine is started, and when it is desired to lift material from the oil well, the cap 57, by means of the lever 56, is moved outwardly, thereby carrying outwardly the collar 49 which in turn moves outwardly the arms 53 and the dogs 45, the heads 46 of which push against the studs 47, and as the dogs 45 are pivoted to the ears 44 on the disk 36, the disk 35 with its sleeve 33 and its disk 34 are moved away from the disk 36 so that the disk 34 will press against the pulley 15 and thereby bind it against the disk 20 which as has been stated, is secured to the sleeve 19 keyed to the shaft 16. By this means the pulley 15 will rotate, driving the belt 14, which is mounted on a pulley on the band wheel 13, in the usual manner. When the direction of the oil well apparatus is to be reversed, by means of the lever 56, the collar 49 is moved inwardly, the inner surface of the collar 49 being rounded so that it will lift the arms 52 of the dogs 41, and as the heads 42 of the said dogs contact with the studs 43, the dogs 41, which are pivoted to ears 40 secured to the disk 35 will move the disk 35 with its sleeve 33 and its disk 34 outwardly so that the disk 34 will press the pulley 17 against the flange 38 on the disk 36, at the same time releasing the pulley 15 so that it is no longer driven by means of the disk 20. By this action the pulley 17 is driven by means of frictional contact with the flange 38 on the disk 36, the disk 36 being secured to the extension shaft 21 as has been set forth. The cable 18, which is mounted on the pulley 17 is crossed so that it will drive the pulley 60 and thereby the band wheel, in the direction opposite to that in which it was previously driven by the belt 14. The outer bearing 22 in connection with the tie 130

rod 28 prevents any fracture of the shaft or of the clutch which might otherwise be possible by abnormal movement of the engine, due to vibrations.

5 As the pulley 60 is bolted to the band wheel 13, it is unnecessary to alter the band wheel, its shaft or its bearings when our improvement is adjusted. This is so although the space in which to work is extremely limited, for it is understood that our improvement is designed to be applied to the band wheel, engine bed, engine shaft and bearings of the usual type of oil well apparatus now in use and which are usually 15 driven by steam engines. As the pulley 60 is narrow, with the groove in its periphery, its connection with the band wheel 13 does not require any readjustment of the band wheel or its bearings. The rope 11 which is 20 crossed and which connects the pulley 60 with the pulley 17, is quite strong enough for the work, as its duty is to let the tools and implements down into the well, the belt 14, connecting the pulley 15 with the band 25 wheel 13 serving to lift the tools and material.

Our improvement may be applied to any standard make of oil well apparatus of regulation type by only replacing the steam 30 cylinder with a cylinder of an internal combustion engine and adjusting our attachment as has been described, without altering the other members of the oil well apparatus or changing their relationship.

35 Having thus described our invention, we claim as new and desire to secure by Letters Patent:

1. In an oil well apparatus, a shaft, an outer disk secured to the shaft to turn therewith, a second outer disk, a sleeve mounted on the shaft, two disks secured to the sleeve, a pulley mounted between the two last named disks, a second pulley mounted between one of the two last named disks and 45 one of the outer disks, and means for moving the sleeve to and from the second outer disk, one of the outer disks being adapted to engage a surface of the first named pulley, the sleeve and the outer disk being 50 adapted for rotating with the shaft, and a flange on the second outer disk which is adapted for engaging the surface of the second pulley.

2. In an oil well apparatus, a shaft, two outer disks secured to the shaft to turn therewith, a sleeve mounted on the shaft in close proximity to one of the said disks, two disks secured to the sleeve, a pulley mounted between the two last named disks, 55 a second pulley mounted between one of the two last named disks and one of the outer disks, there being a flange on one of the outer disks which is adapted for engaging a surface of the first-mentioned pulley, and 60 means for moving the sleeve so that one of

its disks will engage either one of the two pulleys as desired.

3. In an attachment for oil well apparatus, a shaft, a disk secured thereto, a sleeve mounted on the shaft, a disk secured to the sleeve, a pulley disposed between the two disks, and means connected with the sleeve and which projects through an opening in the first-mentioned disk by which the position of the sleeve may be shifted relatively 75 to the first-mentioned disk.

4. In an oil well apparatus, a shaft, two outer disks, a sleeve disposed in close proximity to one of the outer disks, two disks secured thereto, a pulley mounted between the two last named disks, a second pulley mounted between the sleeve and the outer disk disposed at a distance therefrom, and means for moving the disk secured to the sleeve which is disposed on the outer side of 85 the first named pulley, two of the disks being mounted to rotate with the shaft, the outer disks being each adapted to engage a surface of one of the pulleys.

5. In an oil well apparatus, a shaft, two outer disks, a sleeve disposed in close proximity to one of the outer disks, two disks secured to the sleeve, a pulley mounted between the two last named disks, a second pulley mounted between the sleeve and the outer disk disposed at a distance therefrom, two of the disks being mounted for rotating with the shaft, the outer disks being each adapted for engaging a surface of one of the pulleys, ears secured to the outer disk 100 disposed near the sleeve, ears secured to the disk secured to the sleeve which is disposed next to the last named outer disk, the last named ears passing through openings in the last named outer disk, dogs pivoted to the 105 ears, studs secured to the said disk secured to the sleeve which pass through openings in the said outer disk, and studs secured to the last named outer disk, the dogs on the ears on the outer disk being adapted for engaging the studs on the said disk secured to the sleeve and the dogs on the ears on the disks secured to the sleeve being adapted for engaging the studs on the said outer disk.

6. In an oil well apparatus, a shaft, two outer disks, a sleeve disposed in close proximity to one of the outer disks, two disks secured to the sleeve, a pulley mounted between the two last named disks, a second pulley mounted between the sleeve and the outer disk disposed at a distance therefrom, two of the disks being mounted for rotating with the shaft, the outer disks being each adapted for engaging a surface of one of the pulleys, ears secured to the outer disk 115 disposed near the sleeve, ears secured to the disk secured to the sleeve which is disposed next to the last named outer disk, the last named ears passing through openings in the last named outer disk, dogs pivoted to the 120

ears, studs secured to the said disk secured to the sleeve which pass through openings in the said outer disk, studs secured to the last named outer disk, the dogs on the ears on the outer disk being adapted for engaging the studs on the said disk secured to the sleeve and the dogs on the ears on the disks secured to the sleeve being adapted for engaging the studs on the said outer disk, and 10 a collar on the shaft, the collar being adapted for sliding to operate the dogs.

7. In an oil well apparatus, a shaft, two outer disks, a sleeve disposed in close proximity to one of the outer disks, a disk secured thereto, two pulleys, one disposed on each side of the disk secured to the sleeve, three of the disks being mounted for rotating with the shaft, the outer disks being each adapted for engaging a surface of one 20 of the pulleys, there being openings in the outer disk disposed in close proximity to the sleeve, and means projecting through the openings, which are adapted for moving the sleeve relatively to the said outer disk.

25 8. In an oil well apparatus, a shaft, two outer disks, a sleeve disposed in close proximity to one of the outer disks, a disk secured thereto, two pulleys, one disposed on each side of the disk secured to the sleeve, two of the disks being mounted for rotating with the shaft, the outer disks being each adapted for engaging a surface of one of the pulleys, there being openings in the outer disk disposed in close proximity to the 35 sleeve, means projecting through the openings, which are adapted for moving the sleeve relatively to the said outer disk, and means for operating the said means.

9. In an oil well apparatus, a shaft, two 40 outer disks, a sleeve disposed in close proximity to one of the outer disks, a disk secured thereto, two pulleys, one disposed on each side of the disk secured to the sleeve, two of the disks being mounted for rotating 45 with the shaft, the outer disks being each adapted for engaging a surface of one of the pulleys, there being openings in the outer disk disposed in close proximity to the sleeve, means projecting through the openings, which are adapted for moving the sleeve relatively to the said outer disk, a collar on the shaft, the collar being adapted for operating the said means, there being an annular groove in the collar, and an arm 50 adapted to be disposed in the groove for operating the collar.

55 10. In an oil well apparatus, an engine shaft, a sleeve keyed thereto, an outer disk on the sleeve, an extension shaft secured to the sleeve, a second outer disk secured to the extension shaft, a second sleeve mounted on the extension shaft near the second outer disk, a disk secured to the second sleeve, two pulleys, one mounted on either side of 60 the last named disk, and means projecting

through an opening in the second outer disk which are adapted for moving the second pulley relatively to the second outer disk.

11. In an oil well apparatus, an engine shaft, a sleeve keyed thereto, an outer disk 70 on the sleeve, an extension shaft secured to the sleeve, a second outer disk secured to the extension shaft, a second sleeve mounted on the extension shaft near the second outer disk, a disk secured to the second sleeve, two 75 pulleys, one mounted on either side of the last named disk, means projecting through an opening in the second outer disk which are adapted for moving the second pulley relatively to the second outer disk, a collar 80 on the shaft which is adapted for operating the said means, there being a groove in the collar, and an arm being disposed in the groove for operating the collar.

12. In an oil well apparatus, a shaft, a 85 sleeve keyed to the shaft, an extension shaft secured to the sleeve, two pulleys mounted with the axis of the shaft as their center, three disks, each of the pulleys being disposed between two of the disks, and means 90 for moving the middle disk from one pulley to the other, the disks being so secured that when a pulley is clamped between two of the disks, it will rotate with the shaft.

13. In an oil well apparatus, a shaft, a 95 sleeve keyed to the shaft, an extension shaft secured to the sleeve, a sleeve mounted on the extension shaft, a disk secured to the sleeve, two pulleys, one of which is mounted on the last named sleeve and the other of 100 which is mounted on the other side of the last named disk, two additional disks one disposed on the outer side of each of the pulleys, and means projecting through an opening in one of the last named disks 105 which are adapted for moving the sleeve so that the first named disk may be brought in contact with either of the pulleys.

14. In an oil well apparatus, a shaft, a 110 sleeve keyed to the shaft, two pulleys mounted with the axis of the shaft as their center, three disks, each of the pulleys being disposed between two of the disks, means for moving the middle disk from one pulley to the other, the disk being secured so that when a pulley is clamped between two of the disks it will rotate with the shaft, an outer bearing for the extension shaft, and means for connecting the bearing with the engine so that the shaft 115 or extension shaft will not be broken by abnormal vibrations of the engine.

15. In an attachment for oil well apparatus, a shaft having a shoulder, two disks secured to the shaft, one at each side of the shoulder, a sleeve mounted on the shaft at one side of the shoulder, a disk secured to one end of the sleeve, a pulley mounted on the shaft between one of the two first-mentioned disks and the disk on the sleeve, 130

and a second pulley mounted on the sleeve between the other of the two first-mentioned disks and the disk on the sleeve.

16. In an attachment for oil well apparatus, a shaft, two outer disks secured to rotate with the shaft, a sleeve mounted on the shaft between the outer disks, a central disk secured to the sleeve, two pulleys, one disposed at each side of the central disk, both pulleys being disposed between the outer disks, the disks being adapted to engage the sides of the pulleys respectively, and means connected with the sleeve and which projects through an opening in one of the outer disks by which the position of the sleeve may be shifted relatively to the outer disks.

17. In an attachment for oil well apparatus, a shaft having a shoulder, two disks secured to the shaft, one at each side of the shoulder, a sleeve mounted on the shaft at one side of the shoulder, a disk secured to one end of the sleeve, a pulley mounted on the shaft between one of the two first-mentioned disks and the disk on the sleeve, a second pulley mounted on the sleeve between the other of the two first-mentioned disks and the disk on the sleeve, and means connected with the sleeve and which project through an opening in one of the two first-mentioned disks by which the position of the sleeve may be shifted relatively thereto.

18. In an attachment for oil well apparatus, a shaft, a disk secured to the shaft, a sleeve mounted on the shaft, a disk secured to the sleeve, a pulley disposed between the two said disks, an additional disk secured to the sleeve, dogs pivoted to the first-mentioned disk, studs secured to the said additional disk, the studs projecting through openings in the first-mentioned disk adapted

to be engaged by the dogs, and means adapted for operating the dogs.

19. In an attachment for oil well apparatus, a shaft, a disk secured to the shaft, a sleeve, a disk secured to the sleeve, dogs pivoted to one of the disks, studs mounted on the other disk which project through openings in the disk to which the dogs are pivoted, the studs being adapted to be engaged by the dogs, an additional disk secured to the sleeve at a distance from the first-mentioned disks, a pulley disposed on the sleeve between the two disks secured thereto, and a collar disposed on the shaft adapted to engage the dogs to operate them.

20. In an attachment for oil well apparatus, a shaft, a sleeve upon said shaft, two disks spaced apart and secured to the sleeve, a pulley mounted on the sleeve between the two disks, a disk secured to the shaft in close proximity to one of the disks secured to the sleeve, the disk which is secured to the shaft having openings therein and having a flange which is adapted to engage the face of the pulley, lugs secured to one of the disks secured to the sleeve, the lugs projecting through the openings in the disks secured to the shaft, and dogs pivoted to the lugs, the dogs being adapted to engage members of the disk secured to the shaft to move the sleeve with its two disks relatively to the disk secured to the shaft.

In testimony whereof we have signed our names to this specification in the presence of two subscribing witnesses.

JOHN WALTER LEONARD.
HARRY EDGAR BROWN.
